(57) **CLAIM**

The ornamental design for a high-visibility display rack, as shown and described.

DESCRIPTION

FIG. 1 is a front perspective view of an embodiment of the high-visibility display rack

FIG. 2 is a front elevation view of the high-visibility display rack of FIG. 1;

FIG. 3 is a side elevation view of the high-visibility display rack of FIG. 1, both sides being identical;

FIG. 4 is a rear elevation view of the high-visibility display rack of FIG. 1;

FIG. 5 is a top plan view of the high-visibility display rack of FIG. 1;

FIG. 6 is a bottom plan view of the high-visibility display rack of FIG. 1;

FIG. 7 is a front perspective view of the high-visibility display rack of FIG. 1, mounted to a support; and,

FIG. 8 is a side elevation view of the high-visibility display rack of FIG. 7, mounted to a support.

The dotted lines indicate components for illustrative purposes only and form no part of the subject design relative to the particular embodiment shown.
